UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,103,900.

Specification of Letters Patent. Patented July 14, 1914.

Application filed May 20, 1913. Serial No. 768,713.

To all whom it may concern:

Be it known that I, CORMELIUS B. CORCORAN, a citizen of the United States, residing in New York, in the county of New York and State of New York, have invented certain new and useful Improvements in Type-Writing Machines, of which the following is a specification.

My invention relates to a sheet guard for attachment to typewriting machines. When a breeze from an open window or an electric fan strikes the work sheets, especially when manifolding, the paper being very light and filmy, the sheets are raised and oftentimes tumbled over the front of the machine, obscuring the operator's view of the writing line, or perhaps become tangled with the type-bars and torn, and sometimes caused to wrinkle and fold. To overcome such difficulties I have devised convenient means for holding down the work sheets upon the paper table. The invention prevents their being raised and becoming disarranged, yet permits them a certain amount of freedom in order that they may be fed along without hindrance as the writing proceeds.

I construct the device in a manner to facilitate introduction of the work sheets, by raising or swinging the guard away from the paper table, and I also provide means to lock the guard when it is returned to its effective position. The guard is preferably formed with a curvature conforming to that of the bead on the upper edge of the usual paper table, so that when it is not desirable to use the guard it may be locked down into position and the work sheets be fed over said guard.

Other features and advantages will hereinafter appear.

In the accompanying drawings, Figure 1 is a perspective view showing my improvement applied to the paper table of a typewriting machine. Fig. 2 is a side elevation of the platen frame, showing the normal position of the work sheets and the location of the guard with its edge beyond the highest point of the paper table as indicated by the line *a*. Fig. 3 is a view showing how the sheets are prevented from tumbling forward by the guard and their tendency to fall backwardly. Fig. 4 is a detail view of the locking device for the guard. Fig. 5 is a view showing the guard partly raised for the introduction of the work sheets.

The work sheets 1 are usually supported on a paper table 2 fixed between the platen frame ends 3, to be guided into the bite of the feed rolls 4 and the platen 5, and fed along at line-space intervals. The sheets 60 hang down over the rear of the paper table, and are apt to be raised by a breeze and tumbled over the front of the machine. To prevent this, I arrange a guard plate 6 parallel with the bead 7 on the rear edge of the paper table 2. This guard is supported from the platen frame ends 3, by means of brackets 8, 9 arranged to project the edge 10 of the guard to a point beyond the center of the bead 7 indicated by the line *a* in Fig. 2, so that when the sheets are raised by the breeze, they will have a tendency to bulge out as shown in Fig. 3 to the rear of the paper table, and as they receive no support there, they will drop to their former positions. To 75 facilitate introducing the sheets beneath the guard 6, one of the brackets 8 may be hinged at 11 to the platen frame end 3 to permit the guard to be swung up out of the way, while the sheets are inserted. The guard can be 80 locked in position over the sheets by providing the bracket 9 with projections or hooks 12 capable of being slightly contracted, being for this purpose slotted at 13, while being forced through slot 14 of plate 15 85 fixed on a platen frame end 3. The hooks expand after passing through the plate 15, and firmly grip the latter.

Variations may be resorted to within the scope of the invention, and portions of the 90 improvements may be used without others.

Having thus described my invention, I claim:

1. In combination with the paper table of a typewriting machine, a bead along the 95 upper edge of said paper table, and a guard plate extending parallel to and above said bead, said guard being curved to conform with the curvature of said bead.

2. In combination with the paper table of 100 a typewriting machine, a guard plate extending parallel to and above the edge of said paper table, said plate being concavo-convex in cross section, and means for moving said guard plate away from said paper 105 table.

3. In combination with the paper table of 110 a typewriting machine, a guard plate extending parallel to and above the edge of said paper table, said guard plate having hinge

connection at one end whereby it may be moved away from said paper table, and means to lock said guard plate at the opposite end thereof in its effective position.

5 4. In combination with a platen frame, a paper table connected therewith, and means on said platen frame for supporting a guard plate parallel to and above the edge of said paper table.

10 5. In combination with a platen frame, a paper table connected therewith to guide work sheets to the platen, and a guard plate supported on the platen frame parallel to the edge of said paper table over said work
15 sheets.

6. The combination with a paper table of

a typewriting machine and a platen frame, said paper table having a curved upper edge, of a paper guard plate of similar curvature to that of the upper edge of said paper table 20 and spaced therefrom for the passage of work-sheets, and end-supporting brackets for said guard plate, one of said brackets having a hinged connection to the platen frame that said guard plate may thereby be swung 25 out of operative position, and the opposite bracket having means for locking engagement with said platen frame.

CORNELIUS B. CORCORAN.
